DORF, GERMANY.

AUTOMATIC FIREARM.

Application filed May 19, 1928, Serial No. 279,131, and in Germany April 27, 1926.

Our invention relates to an automatic fire arm to which the cartridges are fed from the side, and has for its object to afford the possibility of a great number of shots to be fired 5 uninterruptedly, and to avoid, notwithstanding, the employment of voluminous and heavy magazines hitherto required therefor.

The invention substantially consists in the fact, that the fire arm is designed to simultaneously receive two separate cartridge magazines, adapted to be exchanged independently of one another and to be brought by suitable means successively into the range of the members of the arm that shift the 15 cartridges in the direction of the bore of the barrel into the cartridge chamber of the latter.

The invention further comprises means for alternately adjusting automatically the one 20 or the other of the two magazines for the feed of the cartridges and to cause, when one magazine is empty, the fire to be continued from the other magazine. Means are further provided, by which the feed from a magazine 25 may be interrupted at any time, even if it is not yet emptied, whereupon the other magazine automatically undertakes the further feed of cartridges.

Furthermore, in order to not have extended 30 undesirably, after both magazines have been emptied, the interruption of the fire that arises due to the insertion of new full magazines, by starting anew the automatic operation of the arm by hand, whereby much time 35 is occupied, a mechanism is provided, by which the firing of the last present cartridge, after being shifted into the cartridge chamber, is automatically rendered impossible, by the trigger mechanism of the arm being 40 locked. Only by the insertion of a full magazine in the magazine chamber the possibility of uninterruptedly firing is re-established.

In order to allow of our invention to be 45 more easily understood, a preferred embodiment of same is illustrated in the accompanying drawings as applied to an automatic barrel recoil firm arm. In these drawings:

Figure 1 is a cross section of the arm seen 50 from the muzzle toward the magazine mechanism, two cartridge magazines being inserted,

Figure 2 is a top view of the magazine mechanism,

Figure 3 is the lateral view of an empty 55 opened magazine,

Figure 4 is a similar view of a full magazine,

Figure 5 is a top view of a full magazine, Figures 6 and 7 are a lateral and top view, respectively, of a detail of the magazine 60 chamber.

The magazine chamber.

A case *b* serves as slide for the barrel and for the breech sleeve *a* connected thereto, 65 which case has laterally arranged on it the magazine chamber *c* which is open on its outer end. A horizontal partition *c*¹ divides the chamber *c* into two compartments each adapted to lodge a cartridge magazine. The upper 70 and lower wall of the chamber *c* has pocket-like rises *c*² to enable parts projecting from the magazines to freely pass.

When the barrel assumes the firing or run out position, the passage opening, leading to 75 the bore of case *b*, of the magazine chamber *c* is closed by the outer wall of the breech sleeve *a*, whilst with the barrel in recoil position, an aperture forming the cartridge inlet, of sleeve *a* registers with said chamber opening, 80 both compartments of the magazine chamber opening into the cartridge inlet. Two lip-shaped cartridge feeders *d*, *d* project, respectively, from the upper and lower chamber wall into the path of the breech sleeve *a*, 85 which feeders are mounted on these walls and, when the barrel is in firing position, pass into slots *a*¹ provided in sleeve *a*.

The cartridge magazines.

The cartridge magazines *e*, Figures 3-5, 90 consist of thin-walled sheet metal boxes open on one of their narrow sides and are each provided with a feeder *e*² adapted to be shifted under the action of a feed spring *e*¹ in the direction toward their opening. The cartridges are inserted in the magazine transversely of their longitudinal axis, whereby the feeder *e*² is urged back and the feed spring *e*¹ is tensioned.

The opening of the magazine box is closed 100 by a lid *f* that is provided with means for locking it in open and closed position. To this end locking bolts *g*² are vertically shiftably mounted in guide blocks *g* on those of 105 the broad sides *f* of the boxes, which, after

the box has been inserted in the chamber c , abut on the upper and lower wall thereof, see also Figure 1. The locking bolts g^2 are provided with notches g^1 and pressed outward by flat springs g^3 arranged below them. In this outer position the bolts g^2 lock the lid f in the closing position against an opening motion, by hooks f^1 abutting on the stem of the bolts g^2 . Upon depressing however the bolts g^2 , the notches g^1 arrive opposite the hooks f^1 of the lid f . The latter is then lifted by hand or by the pressure exerted by the cartridges contained in the box, and is secured against an automatic closing motion by its hooks f^1 engaging the notches g^1 . Upon a pressure being exerted on the lid f , the hooks f^1 release the notches g^1 , the lid passes to closing position and is again locked therein by the locking bolts g^2 being lifted under the action of the springs g^3 .

Mechanism for alternately and automatically adjusting to feed position the introduced magazine boxes.

- 25 The adjustment of a full cartridge magazine box e in a condition to feed a cartridge to the barrel takes place by opening the lid f by the action of a releasing mechanism provided on each magazine compartment. When 30 a magazine box e is inserted in a compartment, its lid f is in closed position and the upwardly projecting locking bolts g^2 glide unhinderedly into the above-mentioned pocket c^2 .
- 35 A shaft h is mounted each on the upper and lower chamber wall, see Figures 1 and 2, each of which shafts has so fixed on it two releasing levers h^1 that their cam-shaped ends h^2 , that project into recesses of the chamber walls, are opposite the above described locking bolts g^2 of the magazine boxes e . The 40 rocking motion of the shafts h is derived from the inserting and withdrawing motion of the magazine boxes.
- 45 On the side walls of the compartments are arranged casings i in which rods i^1 are lodged so as to be shifted toward the barrel under the action of springs i^2 . Levers h^3 fixed on each shaft h engages each a slot of the respective rod i^1 and thus serve to transmit the shifting motion of the rods i^1 to the shafts h in one or other direction and to convert it into a rocking motion of these shafts. The shaft h mounted on the upper compartment 50 and acting by its releasing levers h^1 upon the inserted magazine box, is in mesh with the rod i^1 of the lower compartment and vice-versa.
- 55 When the compartments are empty, the cam ends h^2 of all releasing levers h^1 project under the action of the springs i^2 into the path of the magazine locking bolts g^2 of the lids f , which bolts assume their upper position. When a box e is inserted in one of the 60 compartments, e. g. in the upper one, noses

e^3 that project on the box wall, see Figures 3 to 5, take with them the rods i^1 , whereby the springs i^2 are tensioned, and thereby rock the shaft h of the lower compartment and therewith the lower releasing levers h^1 out 70 of their operative position. At the same time the locking bolts g^2 of the inserted upper box hit the cams h^2 of the upper releasing levers and are depressed by them. Consequently the lid f of the upper box is lifted under the 75 pressure acting upon it by the cartridges and is locked in open position by the bolts g^2 and hooks f^1 , as above described.

The magazine box e introduced in the upper compartment is thus adjusted for feeding 80 a cartridge, whilst the releasing mechanism of the lower compartment has been brought into an inoperative position. The lid f of a box introduced later on in the lower compartment remains closed. This lower box 85 however rocks out of operation the releasing levers h^1 for the lid f of the upper box e . This lid thus remains unacted upon in the locked open position.

When the upper box is withdrawn, the 90 springs i^2 of the upper compartment are relaxed by the simultaneous withdrawal of the noses e^3 , while the lid f of the lower box e is automatically opened by the lower releasing levers h^1 being rocked. Only one single 95 box is thus open and adapted to supply cartridges.

In order to fix the boxes in their extreme position within the compartments against the action of the feed springs e^1 and springs i^2 , 100 two locking levers k^1 are rigidly fixed on an upper and lower shaft k , the hook-shaped ends of which levers engage through suitable slots of the compartment walls each a nose e^4 of the box walls. By springs k^2 coiled on 105 the shaft k the locking levers k^1 are pressed toward the box wall, see Figure 1. When a box e is introduced, its noses e^4 lift the locking levers k^1 , whereupon the hook ends of the latter engage behind the noses e^4 and thus 110 lock the box against the action of the springs i^2 and e^1 .

The locking levers k^1 may be disengaged by hand by means of the handles k^3 rigid on the shaft k . When the locking levers k^1 are 115 disengaged by manipulating the handles k^3 , the respective box e is automatically ejected from its compartment by the action of the springs i^2 .

The described release of the magazine locking mechanism may only be executed after the lid f of the respective box has been closed, as otherwise the cartridges still contained in the box would be ejected by the feed spring e^1 and would deposit in the respective compartment. To prevent this, a lid closing lever l is fixed on each shaft k , the curved end of which lever abuts on the open lid f in the midst thereof, of a box that is present in locked position in the respective compartment. 120 125 130

ment. Upon releasing the locking levers k^1 by means of the handle k^3 the lid closing lever l depresses the opened lid f into closing position, whereby the engagement of the locking bolts g^2 and hooks f^1 is suppressed. When arrived however in closing position, the lid f is at once locked again by the bolts g^2 . Upon the box then being ejected by the springs i^2 , at the same time the lid f of the other box 10 that remains in its compartment, is automatically opened.

When a magazine box, e. g. the upper one, has been unlocked and ejected, the releasing levers h^1 of the lower compartment, which 15 levers now press upon the bolts g^2 of the lower box due to the upper springs i^2 being relaxed, and open the lid f of this box, will not allow of the lower box to be unlocked by the handle k^3 and of its lid f to be closed simultaneously. 20 To permit this nevertheless, handles i^3 are provided on the rods i^1 , by means of which handles a temporary lifting of the releasing levers h^1 may be obtained when the lower box should likewise be unlocked by hand.

25 In order to automatically close an emptied magazine box and simultaneously opening the other full one, the following mechanism is provided. An unlocking lever m fulcrumed at m^1 on the chamber wall is provided symmetrically for each magazine box. The end m^2 of these levers forms a stop and projects through a recess of the chamber wall into the path of a projection e^6 provided on the feeder e^2 and projecting from the side wall of the 30 box and running in a slot e^5 of the latter. After the last cartridge has left the magazine box and entered the breech of the arm, so that the box is empty, the projection e^6 of the feeder e^2 hits the stop m^2 of the unlocking 35 lever m and rocks the latter about its fulcrum so that lever m by means of a face m^3 that abuts on the locking lever k^4 , rocks the magazine locking mechanism k , k^1 in the unlocking direction, while at the same time the lid f 40 is closed by the appurtenant lid closing lever l . The empty closed magazine box is thereupon ejected and may be re-filled and introduced anew, while in the meanwhile cartridges are supplied from the other magazine 45 box.

Automatic trigger locking mechanism.

An automatic trigger locking mechanism is provided allowing of the possibility of firing to be suppressed after the last cartridge 55 has been fed from a magazine box to the barrel. To this end noses e^7 are provided near the front end of the magazine boxes, which noses, when the boxes are inserted in the compartments, strike against double levers n pivoted on the front wall of chamber c and rock these levers in such a manner, that the other ends of the latter, that engage suitable recesses of a shiftable rod o , Figures 1 and 2, 60 shift this rod against the action of a spring 65

p . This spring p is tensioned, as soon as any magazine box is introduced, and remains tensioned, as long as any box is being lodged in locked state in the compartments. A double-armed interrupting lever q is fulcrumed on the chamber c , the one arm of which lever q 70 engages another recess provided in the rod o , while its other arm q^1 is in connection with the trigger mechanism (not shown) and acts as a locking member therefor. When at least 75 one box is in the chamber c , the lever arm q^1 is out of the range of the trigger mechanism. The single box still in the chamber c is ejected by unlocking it manually or after 80 the last cartridge has been fed therefrom to the barrel, the lever n follows under the action of spring p the nose e^7 that now gives way toward the right, rod o is shifted and locks the locking member (lever arm) q^1 of the interrupting lever q into a position in 85 which it locks the trigger mechanism. Hence, the last cartridge is introduced still in the cartridge chamber of the barrel, but cannot be fired, before a full box e has been inserted in the chamber c .

90 A handle q^2 of the interrupting lever q allows of the lever arm q^1 to be released by hand from locking position, so that the trigger is ready to fire the last cartridge that has already been transferred into the barrel. 95

The mechanism for interrupting the firing possibility operates thus in dependence upon the ejecting motion of a box e that has been unlocked within the compartment. In order to warrant this interruption as to the last cartridge, when a failure of ejection of the empty box occurs, as it may be the case e. g. due to a bruised box getting jammed in the compartment, a special safety device is provided that operates independently of the 100 ejecting motion of the box e . To this end the stop face of the lever n , Figures 6 and 7, on which abuts the nose e^7 in inserting a box, is not rigidly arranged on this lever, but is designed as a bolt s shiftably arranged transversely of the inserting direction of the box against the action of a spring. Toward the box the bolt s has a slope face s^1 , on which strikes the projection e^6 of the feeder e^2 , when the last cartridge is supplied from 105 the box to the closure of the arm, shortly before this injection causes the unlocking of the box in co-operation with the locking mechanism m k k^1 . The projection e^6 presses the bolt s out of the range of the box nose e^7 that 110 abuts thereon, so that the lever n passes past the nose e^7 under the action of spring p and the locking member q^1 is rocked into the position to lock the trigger mechanism. 115

Mode of operation.

120 A full magazine box e is firstly inserted in one of the compartments of chamber c , e. g. in the upper compartment, and is automatically locked in its feed position by the locking 125

levers h^1 . Its lid f is then unlocked automatically and opens under the pressure of the cartridges lodged in the box and urged by the feed spring e^1 . The first cartridge abuts on the outer face of the breech sleeve a . The locking member q^1 of the trigger locking mechanism is being rocked into inoperative position, so that this mechanism is ready to fire. Another magazine box that now is inserted in the lower compartment, is firstly waiting therein with closed lid f and in locked state, this box however rocking the lid unlocking mechanism $h^1 h^2$ of the upper compartment into inoperative position.

15 To start the automatic operation of the arm, the barrel is drawn back by hand, while at the same time its closure (not shown) that glides in the breech sleeve a , is opened; whereby the cartridge inlet opening of sleeve a comes to lie opposite the first cartridge of the upper, open magazine box e . This cartridge is shifted under the action of the feed spring e^1 laterally into the path of the sleeve a and is held in this position by the upper feeding lip d and the front edge c^4 of the partition c^1 of chamber c , see Figure 1.

Upon the barrel running out, the rear wall of the cartridge inlet opening of sleeve a shifts the cartridge forward out of the range of the lip d and of the partition c^1 . The next cartridge of the upper magazine box presses the first one into the path of the breech piece (not shown), which then effects in known manner the further shift of the first cartridge 35 into the cartridge chamber of the barrel.

The arm is now in loaded state and for a continuous fire only the operation of the trigger and the supply of full magazine boxes is required to replace the empty and automatically ejected ones. When the last cartridge of the upper box has arrived in the path of the breech sleeve a , the unlocking lever m of the upper compartment lifts under the action of the projection e^6 of the feeder e^2 the locking levers h^1 from the box noses e^4 , while at the same time the lid f of the empty upper box is closed. The latter is then ejected by the action of the springs i^2 , which at the same time unlock the lid f of the lower box 50 through the intermediary of the lid releasing mechanism $h^3 h^1 h^2$. The lower box thereupon undertakes the further feed of cartridges into the path of the movable parts of the breech without any interruption of the fire.

55 The described play of the magazine mechanism is automatically continued so that the arm is continuously firing, until either the trigger is released or no full magazine box is inserted in due time or is not inserted at all 60 instead of an ejected one. In this case the firing possibility is interrupted shortly after the last cartridge has been supplied from the box still present in one of the compartments, by means of the trigger locking mechanism $e^7 e^8 s n o p q q^1$. The last cartridge is still

introduced in the barrel, but perseveres there-in without being fired.

What we claim, is:—

1. In an automatic fire arm a barrel, a breech closure thereon having a lateral cartridge inlet, two frames laterally arranged on a fixed part of the arm opposite said cartridge inlet and opening thereinto, separate cartridge magazines adapted to be introduced in said frames, said magazines each 75 consisting of a box having a cartridge outlet, a spring-actuated feeder arranged in said box and adapted to urge the cartridges toward said outlet and a lid arranged on said outlet and adapted to retain the cartridges 80 in said box.

2. In an automatic fire arm, a barrel, a breech closure thereon having a lateral cartridge inlet, two frames laterally arranged on a fixed part of the arm opposite said cartridge inlet and opening thereinto, separate cartridge magazines adapted to be introduced in said frames, said magazines each 85 consisting of a box having a cartridge outlet, a spring-actuated feeder arranged in 90 said box and adapted to urge the cartridges toward said outlet, a lid arranged on said outlet and adapted to retain the cartridges in said box, and means for automatically locking said lid both in closed and open 95 position.

3. In an automatic fire arm, a barrel, a breech closure thereon having a lateral cartridge inlet, two frames laterally arranged on a fixed part of the arm opposite said cartridge inlet and opening thereinto, separate cartridge magazines adapted to be introduced in said frames, said magazines each 100 consisting of a box having a cartridge outlet, a spring-actuated feeder arranged in 105 said box and adapted to urge the cartridges toward said outlet, a lid arranged on said outlet and adapted to retain the cartridges in said box, means for automatically locking said lid both in closed and opened position, 110 and means for automatically unlocking said lid in closed position upon the box inserting in one of said frames.

4. In an automatic fire arm a barrel, a breech closure thereon having a lateral cartridge inlet, two frames laterally arranged on a fixed part of the arm opposite said cartridge inlet and opening thereinto, separate cartridge magazines adapted to be introduced in said frames, said magazines each 115 consisting of a box having a cartridge outlet, a spring-actuated feeder arranged in said box and adapted to urge the cartridges toward said outlet, a lid arranged on said outlet and adapted to retain the cartridges 120 in said box, means for automatically locking said lid both in closed and open position, means arranged on each of said frames and adapted to unlock in closed position the lid 125 of the box contained in the other frame and 130

for leaving unacted upon the lid locking means of the box contained in the own frame, and vice versa, and for unlocking in closed position the lid of the box contained in said 5 own frame upon the box of the other frame being withdrawn therefrom.

5. In an automatic fire arm a barrel, a breech closure thereon having a lateral cartridge inlet, two frames laterally arranged 10 on a fixed part of the arm opposite said cartridge inlet and opening thereinto, separate cartridge magazines adapted to be introduced in said frames, said magazines each 15 consisting of a box having a cartridge outlet, a spring-actuated feeder arranged in said box and adapted to urge the cartridges toward said outlet, a lid arranged on said outlet and adapted to retain the cartridges in said box, means for automatically locking 20 said lid both in closed and open position, a projection on each of said boxes, a member arranged on each of said frames and adapted to be shifted thereon by said projection upon a box being inserted in said frame, a spring 25 adapted to act against this shift, a lever fulcrumed on each frame and adapted to be rocked by said shiftable member of the other frame, another lever positively connected to 30 said first-named one and adapted to act, when rocked, upon said lid locking means to unlock said lid in closed position.

6. In an automatic fire arm a barrel, a breech closure thereon having a lateral cartridge inlet, two frames laterally arranged 35 on a fixed part of the arm opposite said cartridge inlet and opening thereinto, separate cartridge magazines adapted to be introduced in said frames, said magazines each 40 consisting of a box having a cartridge outlet, a spring-actuated feeder arranged in said box and adapted to urge the cartridges toward said outlet, a lid arranged on said outlet and adapted to retain the cartridges in 45 said box, means for automatically locking said lid both in closed and open position, a projection on each of said boxes, a member arranged on each of said frames and adapted to be shifted thereon by said projection upon 50 a box being inserted in said frame, a spring adapted to act against this shift, a lever fulcrumed on each frame and adapted to be rocked by said shiftable member of the other frame, another lever positively connected to 55 said first-named one and adapted to act, when rocked, upon said lid locking means to unlock said lid in closed position, means for locking said boxes in said frames in feeding 60 position, releasing means for said box locking means, and means for ejecting the emptied boxes from said frames.

7. In an automatic fire arm a barrel, a breech closure thereon having a lateral cartridge inlet, two frames laterally arranged 65 on a fixed part of the arm opposite said car-

tridge inlet and opening thereinto, separate cartridge magazines adapted to be introduced in said frames, said magazines each consisting of a box having a cartridge outlet, a spring-actuated feeder arranged in said box 70 and adapted to urge the cartridges toward said outlet, a lid arranged on said outlet and adapted to retain the cartridges in said box, means for automatically locking said lid both in closed and open position, a projection on each of said boxes, a member arranged on each of said frames and adapted to be shifted thereon by said projection upon a box being inserted in said frame, a spring 75 adapted to act against this shift, a lever fulcrumed on each frame and adapted to be rocked by said shiftable member of the other frame, another lever positively connected to 80 said first-named one and adapted to act, when rocked, upon said lid locking means to unlock said lid in closed position, means for locking said boxes in said frames in feeding position, releasing means for said box locking means, and means for ejecting the emptied boxes 85 from said frames, these means being formed by said spring-actuated shiftable member 90 and said box projection.

8. In an automatic fire arm a barrel, a breech closure thereon having a lateral cartridge inlet, two frames laterally arranged 95 on a fixed part of the arm opposite said cartridge inlet and opening thereinto, separate cartridge magazines adapted to be introduced in said frames, said magazines each 100 consisting of a box having a cartridge outlet, a spring-actuated feeder arranged in said box and adapted to urge the cartridges toward said outlet, a lid arranged on said outlet and adapted to retain the cartridges in said box, means for automatically locking 105 said lid both in closed and open position, a projection on each of said boxes, a member arranged on each frame and adapted to be shifted in the box inserting direction and adapted to be shifted by said projection upon 110 a box being inserted in said frame, a spring adapted to act against this shift, a lever fulcrumed on each frame and adapted to be rocked by said shiftable member of the other frame, another lever positively connected to 115 said first-named one and adapted to act, when rocked, upon said lid locking means to unlock said lid in closed position, means for locking said boxes in said frames in feeding position, releasing means for said box locking means, 120 and means for ejecting the emptied boxes from said frames, these means being formed by said spring-actuated shiftable member and said box projection.

9. In an automatic fire arm a barrel, a breech closure thereon having a lateral cartridge inlet, two frames laterally arranged 125 on a fixed part of the arm opposite said cartridge inlet and opening thereinto, separate cartridge magazines adapted to be introduced 130

in said frames, said magazines each consisting of a box having a cartridge outlet, a spring-actuated feeder arranged in said box and adapted to urge the cartridges toward said outlet, a lid arranged on said outlet and adapted to retain the cartridges in said box, means for automatically locking said lid both in closed and open position, a projection on each of said boxes, a member arranged on each frame and adapted to be shifted by said projection upon a box being inserted in said frame, a spring adapted to act against this shift, a lever fulcrumed on each frame and adapted to be rocked by said shiftable member of the other frame, another lever positively connected to said first-named one and adapted to act, when rocked, upon said lid locking means to unlock said lid in closed position, a pawl pivoted on each frame, a stop face on each box adapted to co-operate therewith so as to lock said box in feeding position, a lever positively connected to said pawl and adapted to act upon the open lid of the respective box so as to unlock said lid in open position upon said pawl being disengaged from said stop face, and means for ejecting the emptied boxes from said frame.

10. In an automatic fire arm a barrel, a breech closure thereon having a lateral cartridge inlet, two frames laterally arranged on a fixed part of the arm opposite said cartridge inlet and opening thereinto, separate cartridge magazines adapted to be introduced in said frames, said magazines each consisting of a box having a cartridge outlet, a spring-actuated feeder arranged in said box and adapted to urge the cartridges toward said outlet, a lid arranged on said outlet and adapted to retain the cartridges in said box, means for automatically locking said lid both in closed and open position, a projection on each of said boxes, a member arranged on each frame and adapted to be shifted by said projection upon a box being inserted therein, a spring adapted to act against this shift, a lever fulcrumed on each frame and adapted to be rocked by said shiftable member of the other frame, another lever positively connected to said first-named one and adapted to act, when rocked, upon said lid locking means to unlock said lid in closed position, a pawl pivoted on each frame, a stop face on each box adapted to co-operate therewith so as to lock said box in feeding position, a third lever positively connected to said pawl and adapted to act upon the open lid of the respective box so as to unlock said lid in open position upon said pawl being disengaged from said stop face, and means for ejecting the emptied boxes from said frames, these means being formed by said spring-actuated shiftable member and said box projection.

11. In an automatic fire arm a barrel, a breech closure thereon having a lateral cartridge inlet, two frames laterally arranged

on a fixed part of the arm opposite said cartridge inlet and opening thereinto, separate cartridge magazines adapted to be introduced in said frames, said magazines each consisting of a box having a cartridge outlet, a spring-actuated feeder arranged in said box and adapted to urge the cartridges toward said outlet, a lid arranged on said outlet and adapted to retain the cartridges in said box, means for automatically locking said lid both in closed and open position, a projection on each of said boxes, a member arranged on each frame and adapted to be shifted by said projection upon a box being inserted therein, a spring adapted to act against this shift, a lever fulcrumed on each frame and adapted to be rocked by said shiftable member of the other frame, another lever positively connected to said first-named one and adapted to act, when rocked, upon said lid locking means to unlock said lid in closed position, a pawl pivoted on each frame, a stop face on each box adapted to co-operate therewith so as to lock said box in feeding position, a third lever positively connected to said pawl and adapted to act upon the open lid of the respective box so as to unlock said lid in open position upon said pawl being disengaged from said stop face, manipulative releasing means for said pawl and said third lever connected thereto, and means for ejecting the emptied boxes from said frames, these means being formed by said spring-actuated shiftable member and said box projection.

12. In an automatic fire arm a barrel, a breech closure thereon having a lateral cartridge inlet, two frames laterally arranged on a fixed part of the arm opposite said cartridge inlet and opening thereinto, separate cartridge magazines adapted to be introduced in said frames, said magazines each consisting of a box having a cartridge outlet, a spring-actuated feeder arranged in said box and adapted to urge the cartridges toward said outlet, a lid arranged on said outlet and adapted to retain the cartridges in said box, means for automatically locking said lid both in closed and open position, a projection on each of said boxes, a member arranged on each frame and adapted to be shifted by said projection upon a box being inserted therein, a spring adapted to act against this shift, a lever fulcrumed on each frame and adapted to be rocked by said shiftable member of the other frame, another lever positively connected to said first-named one and adapted to act, when rocked, upon said lid locking means to unlock said lid in closed position, a pawl pivoted on each frame, a stop face on each box adapted to co-operate therewith so as to lock said box in feeding position, a third lever positively connected to said pawl and adapted to act upon the open lid of the respective box so as to unlock said lid in open position upon said pawl being disengaged from said stop face, and means for ejecting the emptied boxes from said frames, these means being formed by said spring-actuated shiftable member and said box projection.

stop face, means for automatically disengaging said pawl and actuating said third lever after the last cartridge has been supplied to the closure of the arm, and means for ejecting the emptied boxes from said frames.

13. In an automatic fire arm a barrel, a breech closure thereon having a lateral cartridge inlet, two frames laterally arranged on a fixed part of the arm opposite said cartridge inlet and opening thereinto, separate cartridge magazines adapted to be introduced in said frames, said magazines each consisting of a box having a cartridge outlet, a spring-actuated feeder arranged in said box and adapted to urge the cartridges toward said outlet, a lid arranged on said outlet and adapted to retain the cartridges in said box, means for automatically locking said lid both in closed and open position, a projection on each of said boxes, a member arranged on each frame and adapted to be shifted by said projection upon a box being inserted therein, a spring adapted to act against this shift, a lever fulcrumed on each frame and adapted to be rocked by said shiftable member of the other frame, another lever positively connected to said first-named one and adapted to act, when rocked, upon said lid locking means to unlock said lid in closed position, a pawl pivoted on each frame, a stop face on each box adapted to co-operate therewith so as to lock said box in feeding position, a third lever positively connected to said pawl and adapted to act upon the open lid of the respective box so as to unlock said lid in open position upon said pawl being disengaged from said stop face, a rocking lever adapted to lift by its rocking motion said pawl from said stop face and to actuate said third lever, a nose arranged on said spring-actuated feeder of each box and adapted to rock said rocking lever, and means for ejecting the emptied boxes from said frames.

14. In an automatic fire arm a barrel, a breech closure thereon having a lateral cartridge inlet, two frames laterally arranged on a fixed part of the arm opposite said cartridge inlet and opening thereinto, separate cartridge magazines adapted to be introduced in said frames, said magazines each consisting of a box having a cartridge outlet, a spring-actuated feeder arranged in said box and adapted to urge the cartridges toward said outlet, a lid arranged on said outlet and adapted to retain the cartridges in said box, means for automatically locking said lid both in closed and open position, a projection on each of said boxes, a member arranged on each frame and adapted to be shifted by said projection upon a box being inserted therein, a spring adapted to act against this shift, a lever fulcrumed on each frame and adapted to be rocked by said shiftable member of the other frame, another lever positively connected to said first-named one and

adapted to act, when rocked, upon said lid locking means to unlock said lid in closed position, a pawl pivoted on each frame, a stop face on each box adapted to co-operate therewith so as to lock said box in feeding 70 position, a third lever positively connected to said pawl and adapted to act upon the open lid of the respective box so as to unlock said lid in open position upon said pawl being disengaged from said stop face, means for 75 automatically disengaging said pawl and actuating said third lever after the last cartridge has been supplied to the closure of the arm, means for ejecting the emptied boxes from said frames, and manipulative means 80 arranged on said shiftable members and adapted to allow of said lid unlocking levers to be thrown out of their operative position.

15. In an automatic fire arm a barrel, a breech closure thereon having a lateral cartridge inlet, two frames laterally arranged on a fixed part of the arm opposite said cartridge inlet and opening thereinto, separate cartridge magazines each consisting of a box having a cartridge outlet, a spring-actuated 85 feeder arranged in said box and adapted to urge the cartridges toward said outlet, a lid arranged on said outlet and adapted to retain the cartridges in said box, means for automatically locking said lid both in closed and 90 open position, a projection on each of said boxes, a member arranged on each frame and adapted to be shifted by said projection upon a box being inserted therein, a spring adapted to act against this shift, a lever fulcrumed on 95 each frame and adapted to be rocked by said shiftable member of the other frame, another lever positively connected to said first-named one and adapted to act, when rocked, upon said lid locking means to unlock said lid in 100 closed position, a pawl pivoted on each frame, a stop face on each box adapted to co-operate therewith so as to lock said box in feeding position, a third lever positively connected to said pawl and adapted to act upon the open 105 lid of the respective box so as to unlock said lid in open position upon said pawl being disengaged from said stop face, means for automatically disengaging said pawl and actuating said third lever after the last cartridge 110 has been supplied to the closure of the arm, means for ejecting the emptied boxes from said frames, manipulative means arranged on said shiftable members and adapted to allow of said lid unlocking levers to be thrown 115 out of their operative position, and means for crippling the trigger mechanism after a last cartridge has been supplied to the closure.

16. In an automatic fire arm a barrel, a breech closure thereon having a lateral cartridge inlet, two frames laterally arranged on a fixed part of the arm opposite said cartridge inlet and opening thereinto, separate cartridge magazines each consisting of a box 120

having a cartridge outlet, a spring-actuated feeder arranged in said box and adapted to urge the cartridges toward said outlet, a lid arranged on said outlet and adapted to retain the cartridges in said box, means for automatically locking said lid both in closed and open position, a projection on each of said boxes, a member arranged on each frame and adapted to be shifted by said projection upon a box being inserted therein, a spring adapted to act against this shift, a lever fulcrumed on each frame and adapted to be rocked by said shiftable member of the other frame, another lever positively connected to said first-named one and adapted to act, when rocked, upon said lid locking means to unlock said lid in closed position, a pawl pivoted on each frame, a stop face on each box adapted to co-operate therewith so as to lock said box in feeding position, a third lever positively connected to said pawl and adapted to act upon the open lid of the respective box so as to unlock said lid in open position upon said pawl being disengaged from said stop face, means for automatically disengaging said pawl and actuating said third lever after the last cartridge has been supplied to the closure of the arm, means for ejecting the emptied boxes from said frames, manipulative means arranged on said shiftable members and adapted to allow of said lid unlocking levers to be thrown out of their operative position, another nose near the forward end of each box, a crippling lever for the trigger mechanism of the arm, and adapted to be rocked into inoperative position by said last-named nose, upon a box being inserted in one of the frames, a spring adapted to be held tensioned by said nose and to rock said crippling lever into operative position when relaxed by said nose releasing it, and manipulative means arranged on said crippling lever and adapted to rock it into inoperative position independently of said nose.

17. In an automatic fire arm a barrel, a breech closure thereon having a lateral cartridge inlet, two frames laterally arranged on a fixed part of the arm opposite said cartridge inlet and opening thereinto, separate cartridge magazines each consisting of a box having a cartridge outlet, a spring-actuated feeder arranged in said box and adapted to urge the cartridges toward said outlet, a lid arranged on said outlet and adapted to retain the cartridges in said box, means for automatically locking said lid both in closed and open position, a projection on each of said boxes, a member arranged on each frame and adapted to be shifted by said projection upon a box being inserted therein, a spring adapted to act against this shift, a lever fulcrumed on each frame and adapted to be rocked by said shiftable member of the other frame, another lever positively connected to said first-named one and adapted to act, when rocked, upon said lid locking means to unlock said lid in closed position, a pawl pivoted on each frame, a stop face on each box adapted to co-operate therewith so as to lock said box in feeding position, a third lever positively connected to said pawl and adapted to act upon the open lid of the respective box so as to unlock said lid in open position upon said pawl being disengaged from said stop face, means for automatically disengaging said pawl and actuating said third lever after the last cartridge has been supplied to the closure of the arm, means for ejecting the emptied boxes from said frames, manipulative means arranged on said shiftable members and adapted to allow of said lid unlocking lever to be thrown out

on each frame, a stop face on each box adapted to co-operate therewith so as to lock said box in feeding position, a third lever positively connected to said pawl and adapted to act upon the open lid of the respective box so as to unlock said lid in open position upon said pawl being disengaged from said stop face, means for automatically disengaging said pawl and actuating said third lever after the last cartridge has been supplied to the closure of the arm, means for ejecting the emptied boxes from said frames, manipulative means arranged on said shiftable members and adapted to allow of said lid unlocking levers to be thrown out of their operative position, another nose near the forward end of each box, a crippling lever for the trigger mechanism of the arm, and adapted to be rocked into inoperative position by said last-named nose, upon a box being inserted in one of the frames, a spring adapted to be held tensioned by said nose and to rock said crippling lever into operative position when relaxed by said nose releasing it, and manipulative means arranged on said crippling lever and adapted to rock it into inoperative position independently of said nose.

18. In an automatic fire arm a barrel, a breech closure thereon having a lateral cartridge inlet, two frames laterally arranged on a fixed part of the arm opposite said cartridge inlet and opening thereinto, separate cartridge magazines each consisting of a box having a cartridge outlet, a spring-actuated feeder arranged in said box and adapted to urge the cartridges toward said outlet, a lid arranged on said outlet and adapted to retain the cartridges in said box, means for automatically locking said lid both in closed and open position, a projection on each of said boxes, a member arranged on each frame and adapted to be shifted by said projection upon a box being inserted therein, a spring adapted to act against this shift, a lever fulcrumed on each frame and adapted to be rocked by said shiftable member of the other frame, another lever positively connected to said first-named one and adapted to act, when rocked, upon said lid locking means to unlock said lid in closed position, a pawl pivoted on each frame, a stop face on each box adapted to co-operate therewith so as to lock said box in feeding position, a third lever positively connected to said pawl and adapted to act upon the open lid of the respective box so as to unlock said lid in open position upon said pawl being disengaged from said stop face, means for automatically disengaging said pawl and actuating said third lever after the last cartridge has been supplied to the closure of the arm, means for ejecting the emptied boxes from said frames, manipulative means arranged on said shiftable members and adapted to allow of said lid unlocking lever to be thrown out

- of their operative position, another nose near the forward end of each box, a crippling lever for the trigger mechanism of the arm, and adapted to be rocked into operative position by said last-named nose, upon a box being inserted in one of the frames, a spring adapted to be held tensioned by said nose and to rock said crippling lever into operative position when relaxed by said nose releasing it, that is when the respective box is ejected, and means for rocking said crippling lever into operative position in case of failure of the box ejection.
19. In an automatic fire arm a barrel, a breech closure thereon having a lateral cartridge inlet, two frames laterally arranged on a fixed part of the arm opposite said cartridge inlet and opening thereinto, separate cartridge magazines each consisting of a box having a cartridge outlet, a spring-actuated feeder arranged in said box and adapted to urge the cartridges toward said outlet, a lid arranged on said outlet and adapted to retain the cartridges in said box, means for automatically locking said lid both in closed and open position, a projection on each of said boxes, a member arranged on each frame and adapted to be shifted by said projection upon a box being inserted therein, a spring adapted to act against this shift, a lever fulcrumed on each frame and adapted to be rocked by said shiftable member of the other frame, another lever positively connected to said first-named one and adapted to act, when rocked, upon said lid locking means to unlock said lid in closed position, a pawl pivoted on each frame, a stop face on each box adapted to co-operate therewith so as to lock said box in feeding position, a third lever positively connected to said pawl and adapted to act upon the open lid of the respective box so as to unlock said lid in open position upon said pawl being disengaged from said stop face, means for automatically disengaging said pawl and actuating said third lever after the last cartridge has been supplied to the closure of the arm, means for ejecting the emptied boxes from said frames, manipulative means arranged on said shiftable members and adapted to allow of said lid unlocking lever to be thrown out of their operative position, another nose near the forward end of each box, a crippling lever for the trigger mechanism of the arm, and adapted to be rocked into operative position by said last-named nose, upon a box being inserted in one of the frames, a spring adapted to be held tensioned by said nose, an intermediate lever adapted to be rocked by said spring and to transmit this rocking motion to said crippling lever so as to rock the latter into operative position upon said spring being relaxed by said nose releasing said intermediate lever, a spring-actuated sliding bolt on said intermediate lever and adapted to co-operate with said nose for rocking said intermediate lever, said bolt having a slope face adapted to co-operate with said feeder nose and to be depressed by it shortly before said feeder nose unlocks its box for ejection, so as to throw said sliding bolt out of the range of said first-named nose.
20. In an automatic fire arm, two magazine chambers, a cartridge magazine adapted to be inserted in each of said chambers and having a cartridge outlet and a spring actuated cartridge feeder, means for securing the cartridge magazine in the magazine chamber, means for automatically cutting out the cartridge feeder of one magazine when the other magazine is feeding cartridges, and means for automatically releasing and ejecting the magazine from which all cartridges have been fired and simultaneously bringing the other magazine into action to feed cartridges therefrom.
- In testimony whereof we have affixed our signatures.
- FRITZ HERLACH.
THEODOR RAKULA.
